UNITED STATES PATENT OFFICE.

ERNEST R. SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS.

MOISTENING DEVICE.

Application filed January 2, 1923. Serial No. 610,306.

To all whom it may concern:

Be it known that I, ERNEST R. SWANSON, a citizen of the United States, residing at Cranston, in the county of Providence,

5 State of Rhode Island, have invented certain new and useful Improvements in Moistening Devices, of which the following is a specification.

This invention relates to improvements 10 in moistening or conditioning devices for use with textile machines.

One object of the invention is to provide a moistening device in which cops and bobbins of yarn or thread may be held immersed in the treating fluid so that the material may be delivered therefrom in a dampened state carrying the proper content 15 of moisture.

Another object of the invention is to 20 provide an immersion trough or tank in which the cops or bobbins are supported on holders, self-contained within the tank, to adapt the yarn to be delivered therefrom to a winding or other machine for conversion 25 in its moistened state.

Another object of the invention is to 30 provide a moistening device in which the cops or bobbins may be conveniently and quickly applied to their holders in the tank and as readily removed therefrom in doffing spent bobbins and replacing them with fresh ones.

Another object of the invention is to 35 provide means for regulating the degree of immersion of the bobbins in the fluid to control the amount of moisture applied to the material thereon.

Another object of the invention is to 40 provide a moistening device having a tank or trough for the fluid, bobbin-holders for supporting the supply-cops or bobbins therein, and individual covers for the bobbins in the tank, all combined in a unitary appliance which may be employed as an attachment for various types of textile machines.

Other objects of the improvement are set 45 forth in the following specification which describes a preferred embodiment of the invention as illustrated by the accompanying drawings. In the drawings:

Fig. 1 is a view of a well known type 50 of winding machine, showing my improved moistening device as applied to use thereon;

Fig. 2, an enlarged, detailed view of the immersion tank of the device, showing the same in cross-section taken in the line 2—2 of Fig. 1;

Fig. 3, a similar view in cross-section 60 taken on the line 3—3 of Fig. 1;

Fig. 4, a longitudinal sectional view of a portion of one of the covers for the tank, taken on the line 4—4 of Fig. 3, and illustrating the manner in which the bobbin 65 is supported from its holder on the under side of the cover;

Fig. 5, a longitudinal sectional view of the end portion of the tank showing the adjustable overflow drain, the socket in the 70 edge of the tank for receiving the hinge-pivot or trunnion of the cover, and also the stop-lug for the cover; and

Fig. 6, cross sectional view similar to 75 Fig. 2 and illustrating a plurality of supply-bobbins supported in series on one of the covers of the immersion tank.

Referring first to Fig. 1 of the drawings, I have preferred to herein illustrate my improved moistening or conditioning device 80 as applied to use with a well known type of winding machine to moisten or otherwise treat yarn or thread during the process of winding it into merchantable cops or packages, or for converting it to other processes in the textile arts. It is to be understood, however, that my improved apparatus is susceptible of adaptation to other uses and may be applied as an attachment 85 to various other types of textile machines.

As herein shown the winding machine 90 comprises a series of units or heads 2 mounted on a bed or table 3 which is supported from the floor on suitable legs 4. Only two winding units or heads 2 are herein illustrated, but usually they are arranged in gangs of six or more, spaced at a convenient distance apart on the bed 3. Each winder 95 comprises, essentially, a rotating winding-spindle or mandrel 5 on which the cop is wound; a reciprocating thread-guide 6 for traversing the yarn on the spindle; and a tension-device 7 for applying tension to the yarn as it feeds to the guide. These 100 several elements of the winding-mechanism and the means for operating the same are well known to those versed in the art and need no detailed explanation. Suffice it to state that the yarn or thread 105 to be wound is supplied from any suitable form 110

of cop or bobbin, usually arranged below the machine, and delivers therefrom to the tension-device 7 which, as herein illustrated, consists of a pair of opposite grids or plates 8 having cross-bars 9 for pressing against the yarn to apply resistance to its draft. The yarn γ draws between the plates 8 and thence leads through a slot or eye in the thread-guide 6 which directs it onto the spindle 5, and as the latter is rotated the yarn is deposited thereon in helical coils to form the layers of a conical or cylindrical package C. Suitable instrumentalities are provided for arresting the operation of the machine when the yarn or thread breaks or its supply is exhausted, and a starting lever 10, shown in Fig. 1, is connected to start the winding operation after the end has been pieced up.

20 In its present preferred form my improved moistening device comprises a relatively long, narrow and shallow tank or trough 11 having means for holding a series of supply-cops or bobbins B in horizontal position therein with their undersides immersed in the fluid in the bottom of the tank. As a convenient arrangement, the trough 11 is supported from brackets 12 clamped to the legs 4 of the winding or other machine, being provided with depending lugs 14 on its bottom which are slotted to receive the bolts 15 employed for clamping the brackets in place.

25 One improved feature of my invention consists in supporting the supply-bobbins on pivoted holders whereby they may be swung downwardly into horizontal position to immerse them in the fluid in the tank; or raised into vertical position to render them easily accessible for piecing up their yarns, and for doffing the empty bobbins and replacing them with fresh supplies. With this end in view, I preferably support the bobbins on holders 18 mounted on hinged

30 covers 20 which normally rest within the open top of the trough or tank 11 to close the space between its sides. Each cover 20 is of hollow, box-like construction and is provided with lateral pivots or trunnions 21 adapted to be received within recessed bearings or sockets 22 in the opposite sides 23 of the tank 11, see Figs. 3 and 5. At the rear of the trunnions the flat top of the cover 20 is formed with a right-angled web or flange 24, to which is secured the holder 18 for the bobbin B. As shown more particularly in Figs. 3 and 4, the bobbin-holder 18 may consist of a short spindle or mandrel having a reduced, screw-threaded portion 25 inserted through a hole in the depending flange 24 on the cover 20 and secured therein by a nut 27. The spindle 18 is adapted for insertion into the butt end of the wooden yarn-carrier or bobbin-tube b, 65 being usually provided with a plurality of

resilient splines or spring-fingers 28 for gripping the interior of the bore in the tube to secure it in position on the holder 18.

At the forward end of the cover 20 is a depending web or flange 29 which is cut away at its center, see Fig. 2, to provide a flaring opening 30 leading into a slit 31 through which the yarn γ from the bobbin B draws. The top of the cover 20 projects beyond the web 29 in an overhanging ledge or flap 32 which, when the cover is closed down between the sides of the tank, will overlap the rearward end of the next adjacent cover of the series as shown in Fig. 1. The flap 32 is also provided with a guiding slit 33 for the yarn, similar to the slit 31 in the web 29. It is to be understood that a separate cover is provided for each bobbin in the tank and that the number of bobbins used depends on the number of winding heads or other machine units to which the yarns are to be supplied. It is also brought to attention that if it is required to deliver the yarns to the machine "doubled," or in multiple, a plurality of bobbins may be held side by side on each cover with their several yarns drawing through the single slit 31 or through a plurality of such slits, see Fig. 6. Such an adaption of the device would require only slight modification in the structure and arrangement herein shown and would fall within the purview of the present invention.

To sustain the covers 20 in horizontal position, closed down between the sides of the tank 11, I may employ any suitable stop-lug or rest such as the extension or ear 34 projecting from the side of each cover at its forward end, see Fig. 2. The ear 34 is adapted to rest across the top of the forward side of the tank 11 when the cover is closed and serves as a convenient finger-grip for lifting the cover to erect position as illustrated at the right in Fig. 1. On one side of the trough 11 is a lug or abutment 35 which acts as a stop to hold the cover 20 in its upright position.

At one end of the tank or trough 11 is a fluid-leveling overflow or outlet 36 which may be connected to a pipe 37 leading to a suitable drain in the floor. The overflow nipple 36 is screwed through a hole in the bottom of the tank 11 and secured in place by a check-nut 38 tightened against a washer 39. By loosening the nut 38 the nipple 36 may be adjusted with its upper end at the proper height above the bottom of the tank to regulate the depth of the fluid therein, any excess fluid overflowing through the drain; and in this way the depth of immersion of the bobbin may be varied in accordance with any particular requirement. A suitable cock or faucet 40 connected with a water supply may be arranged above the opening at the end of the first cover 20, 130

see Fig. 1, to provide a convenient means for filling the tank.

Having now described the structure and arrangement of a preferred embodiment of the invention in detail, its method of operation will next be explained. In preparing the winding machine for operation the supply-bobbins B are placed on their holders 18 on the covers 20, the covers being raised 10 or tilted into upright position for this purpose as shown at the right in Fig. 1. The yarn y from each bobbin is then led through the guiding slits 31 and 33 at the forward end of the cover, thence drawn through the tension-device 7 to the slot in the thread-guide 6 and its end fastened to the cop-tube on the winding-spindle 5.

The tank or trough 11 is filled with liquid until it overflows through the outlet nipple 36, a suitable emulsion fluid being employed if desired in accordance with any preferred method of conditioning or treating the material. When it is simply required to moisten or dampen the yarn, water may be used 25 as the conditioning agent and in some cases it is softened with soluble oils or emulsified with soap. It has been explained that the overflow nipple 36 is adjustable with respect to the bottom of the tank 11 so that the level 30 of the fluid may be regulated to determine the degree of submersion to which the bobbins are subjected after the covers have been closed down between the sides of the tank. In Fig. 1 the fluid is illustrated at a level 35 substantially coincident with the axes of the bobbins so that the latter are one-half submerged in the bath; but it is obvious that a greater or less degree of saturation of the material on the bobbin may be obtained 40 by raising or lowering the level of the fluid.

After the height of the fluid in the tank has been regulated as required, and the covers 11 closed down to bring the bobbins in horizontal position with their sides immersed in the bath, the winding machine is 45 started to operate in a well known manner to build up the cops or packages on the spindle 5. As the yarn y is taken up by the winding operation it draws off from the supply bobbins B through the guiding slits 31 and 33, and any excess fluid clinging to its surface is scraped off. From the tank 11 the yarn passes between the grids 8 of the tension-device 7 whose cross-bars 50 will further act to scrape off the excess fluid. As the yarn y feeds through the thread-guide 6 to the winding-spindle 5 it is deposited thereon in layers to build up the cop C while being kept moistened to the required 55 degree to facilitate its proper handling and to prepare or condition it for further processes of manufacture.

It has been determined in practice that my improved method of immersing or submerging only a portion of the yarn on the

supply bobbin in the bath results in a more even and uniform distribution of the treating fluid throughout the fibers of the material. I have found that the yarn mass on the bobbin will take up only such a slight 70 content of moisture that no appreciable amount of excess liquid will cling to the surface of the yarn and be carried along to the winding or other operation. Stated briefly, as the yarn draws off from the bobbin it will be moistened at different points along its length with substantially dry portions intervening between the damp stretches. The moisture in the damp patches is, however, eventually distributed over the 80 whole length of yarn by the action of capillary attraction. In other words, the fluid spreads or creeps along the dry portions of the yarn between the moist patches and is taken up by the fibers to saturate the whole 85 structure. In this way I am enabled to dampen or condition the yarn with just the right content of moisture without causing it to carry an excess of the liquid liable to be thrown off to spatter on the machinery 90 and cause rust and corrosion of the metal parts thereof.

With my improved device the dampening or conditioning of the yarn may be regulated to give any desired degree of moisture 95 and no excess fluid is carried along to be thrown off or spattered about; yet the content of moisture is much more evenly distributed with a more uniform effect of the conditioning throughout the whole length 100 of the yarn.

The improved method of supporting the bobbins on the hinged covers of the conditioning or immersion tank makes for greater convenience in applying and doffing the supplies and piecing up the ends, while also protecting the bath from dirt, dust and lint in the air. After the yarn on a bobbin is exhausted it is an easy and simple matter to raise the lid or cover on which it is supported and the empty tube can then be conveniently removed and a full bobbin applied in its place. The means for regulating the level of the fluid in the bath provides for maintaining the bobbins immersed to the 110 desired degree at all times, and the device is extremely simple and economical to manufacture while taking up but little space and being adapted for setting in convenient 115 position within easy reach of the operator. 120

While I have herein illustrated my improved moistening device as applied to use on a winding machine it is obvious that it may be adapted for various other types of textile machinery as employed in the manufacturing arts. It is also to be understood that while I have herein shown and described a preferred arrangement of the device, various modifications may be made in 125 details of construction without departing 130

from the spirit or scope of the invention as expressed in the appended claims.

I claim:

1. In a device for moistening or conditioning textile fibers, the combination with a bath of fluid, of means for maintaining a cop or bobbin non-rotatable and partly immersed in the bath whereby the mass of material thereon will absorb only a predetermined content of the fluid which will be eventually uniformly distributed throughout its fibers without any excess moisture carried thereby.
2. In a device for moistening or conditioning textile fibers, the combination with a bath of fluid, of means for holding a cop or bobbin non-rotatable with one side only immersed in the bath to adapt the yarn or thread to absorb a content of fluid at spaced intervals along its length alternating with intervening dry portions which finally absorb the fluid to provide for a uniform condition of moisture throughout all of the fibers.
3. In a device of the class specified, the combination with a bath of conditioning fluid, of means for holding a cop or bobbin of yarn or thread non-rotatable in horizontal position with its side immersed in the fluid, and means to regulate the degree of immersion of the bobbin in the bath to control the amount of fluid taken up by the material to provide for the proper saturation of the fibers without excess moisture carried thereby.
4. In a device of the class specified, the combination with a tank for the conditioning fluid, of means for holding a cop or bobbin of yarn or thread in horizontal position and non-rotatable in the tank with its side immersed in the fluid, and means to adjust the level of the fluid in the tank to regulate the degree of immersion of the bobbin to control the amount of content of fluid absorbed by the material thereon.
5. In a device of the class specified, the combination of a tank for a bath of conditioning fluid, and means for pivotally supporting cops or bobbins non-rotatable in the tank to adapt them to be partly immersed in the fluid and to be raised away from the bath to facilitate the doffing and replacing of the bobbins and the manipulation of the yarns or threads delivering therefrom.
6. In a device of the type specified, the combination of a tank for a bath of conditioning fluid, and pivoted cop or bobbin-holders adapted to support the bobbins in horizontal position and non-rotatable in the tank with their sides immersed in the fluid and to be tilted into substantially upright position to raise the bobbins out of the bath to facilitate the doffing and replacing thereof and the manipulation of the yarns or threads leading therefrom.

7. In a device of the type specified, the combination of a tank for a bath of conditioning fluid, a plurality of covers pivoted to the sides of the tank to close its top, and bobbin-holders carried by the covers to adapt them to non-rotatably support the bobbins with their sides immersed in the fluid when the covers are closed and to raise the bobbins out of the bath when the covers are opened.

8. In a device of the type specified, the combination of a trough-like tank for a bath of conditioning fluid, a series of covers hinged to the tank to adapt them to close its top, and means for supporting cops or bobbins non-rotatable on the under side of the covers to adapt them to be held with their sides immersed in the bath when the covers are closed and to be raised out of the bath when the covers are opened.

9. In a device of the type specified, the combination of a trough-like tank having sockets arranged along its sides, a plurality of covers provided with trunnions seated in the sockets on the tank to adapt the covers to close down across its top, said covers formed with depending flanges at their rearward ends and overhanging flaps at their forward ends, bobbin-holders projecting at right-angles from the depending flanges on the covers and adapted to non-rotatably support the bobbins to hold them partly immersed in the tank, means for supporting the covers in closed relation on the tank, and means for holding the covers in erect position above the tank.

10. In a device of the type specified, the combination with a trough-like tank for a bath of conditioning fluid, means for supporting bobbins non-rotatable in horizontal position in the tank with their sides immersed in the bath, and an overflow device in the tank adapted for adjustment to control the depth of the fluid to regulate the degree of immersion of the bobbins.

11. In a device of the type specified, the combination with a trough-like tank, of a series of box-like covers pivoted to close within the sides of the tank and provided with forwardly projecting flaps for closing the spaces between the covers, and means for holding cops or bobbins non-rotatable on the under side of the covers to adapt them to be immersed in the fluid in the tank or to be raised out of the bath.

12. In a device of the type specified, the combination with a tank, of box-like covers hinged to the tank to close down between its sides, bobbin-holders supported on the rearward depending side of the covers, and means for guiding the yarns from the bobbins through the forward side and up through the top of the covers.

In testimony whereof I affix my signature.
ERNEST R. SWANSON.
